UNITED STATES PATENT OFFICE.

CHARLES R. BIRDSEY, OF HINSDALE, ILLINOIS, ASSIGNOR TO UNITED STATES GYPSUM COMPANY, OF CHICAGO, ILLINOIS, A CORPORATION OF NEW JERSEY.

PLASTER-BOARD.

1,358,508.

Specification of Letters Patent.

Patented Nov. 9, 1920.

Application filed January 2, 1920. Serial No. 348,941.

To all whom it may concern:

Be it known that I, CHARLES R. BIRDSEY, a citizen of the United States, residing at Hinsdale, in the county of DuPage and State of Illinois, have invented certain new and useful Improvements in Plaster-Board, (Case C,) of which the following is a description.

My invention belongs to that general class of devices known as plaster board or the like, and relates particularly to an improved board which will be simple, pleasing, convenient, durable, satisfactory, and efficient, and which may be accurately and economically manufactured. The invention relates particularly to a type of board in which the body of plaster, plaster Paris, or plastic material or the equivalent is inclosed on one or both face sides and is inclosed on one or both opposite edges, and in which the edges will conform to a desired definite specification as to size and shape. Many other objects and advantages of the construction herein shown and described will be obvious to those skilled in the art from the disclosure herein given.

To this end my invention consists in the novel construction, arrangement and combination of parts herein shown and described, and more particularly pointed out in the claims.

In the drawings, wherein like reference characters indicate like or corresponding parts,

Figure 1 is a sectional view showing a portion of a plaster board embodying the invention.

Fig. 2 is a perspective view of a portion of the same board,

Fig. 3 is a similar view of a slightly modified construction.

Referring to the drawings, particularly Figs. 1 and 2, 1 represents a body of suitable material, as for example, plaster, plaster Paris, or any equivalent suitable for the purpose, which may be handled in a plastic state and thereafter allowed to set or harden. The body is inclosed between the cover sheets 2 and 3 of suitable covering material, and in this connection it may be mentioned that I have found paper, of the desired weight or thickness, very satisfactory for the purpose.

In the type illustrated in Figs. 1 and 2, the two covering sheets are bent or folded over at the edges, it being understood that one or

both edges may be inclosed, so as to inclose the plastic material at the edges of the board. As shown, sheet 2 is folded over as at 4, and the extreme or free edge 5 extended into the body. Ordinarily I prefer to score the sheet as at 6-6 so that the same folds evenly, and gives an even or perfect edge or corner. The sheet 3 is shown folded over as at 7, with the extreme edge 8 also embedded in the body, this sheet being preferred 65 scored as at 9. In forming the board the edges 5 and 8 may be secured together in any suitable manner, preferably by permitting the portion of the plastic material to flow between the two which serves to seal 70 and secure them together.

In the construction shown in Fig. 3, 11 represents the body, and 12 and 13 the two covering sheets. In this case, one sheet as shown in 11 is folded as at 14 and 15, the same being first scored at 16, if desired. The sheet 13 is folded as at 17, being first scored at 19. When constructed as shown in this figure, I prefer to make the folded over portion 17 of a width so that the edge 18 will 80 seat or engage with the folded over portion of the other covering sheet.

It will be noted with these constructions the edge is substantially completely inclosed, as before mentioned this may be at one or 85 both sides. Obviously if the sheets were integral and wrapped over one edge, then only one edge would need to be inclosed. The resulting product has a straight smooth edge, at a perfect desired angle, the board being 90 uniform in width. The completed product has many advantages including increased strength and durability, and is of an improved appearance. During shipping or handling the edges are protected so that 95 there is no tendency to break away and no sifting out of the body at the edge.

Having thus described my invention it is obvious that various immaterial modifications may be made in the same without departing from the spirit of my invention; hence I do not wish to be understood as limiting myself to the exact form, construction, arrangement and combination of parts herein shown and described or uses mentioned.

What I claim as new and desire to secure by Letters Patent is:

1. A plaster board of the kind described, comprising a body of suitable material and 110

cover sheets arranged one on each face side thereof, said sheets being folded over to overlie the edge of the board, the extreme edge portion of one sheet being folded inwardly and embedded in the body, said edge portion of the sheet extending into the body from one edge thereof substantially midway the side faces of the body.

2. A plaster board of the kind described, comprising a body of suitable material, and cover sheets arranged at each side thereof, said sheets folded over the edge of the board and thence inwardly and embedded in the body.

3. A plaster board of the kind described, comprising a body of suitable material, and cover sheets arranged at each side thereof, said sheets folded over the side edges of the board, the extreme edges of said sheets folded inwardly and embedded in the board. 20

In testimony whereof I have hereunto signed my name in the presence of two subscribing witnesses.

CHARLES R. BIRDSEY.
